UNITED STATES PATENT OFFICE.

GEORGE D. HOFFMAN, OF WESTERN SPRINGS, ILLINOIS, ASSIGNOR TO NORWALL MANUFACTURING COMPANY, OF CHICAGO, ILLINOIS, A CORPORATION OF ILLINOIS.

AIR-VENT VALVE.

No. 901,242.

Specification of Letters Patent.

Patented Oct. 13, 1908.

Application filed August 16, 1906. Serial No. 330,769.

To all whom it may concern:

Be it known that I, GEORGE D. HOFFMAN, a citizen of the United States, residing at Western Springs, county of Cook, State of Illinois, have invented a certain new and useful Improvement in Air-Vent Valves, and declare the following to be a full, clear, and exact description of the same, such as will enable others skilled in the art to which it pertains to make and use the same, reference being had to the accompanying drawings, which form a part of this specification.

My invention relates in general to steam heating systems, and more particularly to mechanism for effecting the expulsion of air from the system and for preventing the admission of air to the system when the condensation of the steam produces a pressure less than that of the atmosphere.

It is well known that the lower the pressure to which water is subjected the lower will be the temperature necessary to convert the water into steam. It is frequently desirable in steam heating systems to maintain the lowest pressure practicable in order that steam may be more quickly generated and circulated throughout the system. This result is accomplished by preventing the admission of air to the system when the condensation of steam therein has produced a pressure less than that of the atmosphere. In order that air may be positively and effectively prevented from entering the system when the pressure therein is less than that of the atmosphere, it is necessary that the port leading from the system to the atmosphere should be tightly closed at the time the pressure in the system falls below the atmospheric pressure, otherwise when the decreasing pressure in the system passes below atmospheric pressure, air will be gradually drawn into the system thereby preventing a pressure in the system lower than that of the atmosphere.

The primary object of my invention is to provide a steam heating system with means for permitting the air in the system to be expelled and for effectively preventing the return of air into the system upon the condensation of the steam.

A further object of my invention is to provide an attachment for steam radiators which will freely permit the discharge of air therefrom when the generated steam causes a pressure slightly above that of the

atmosphere, and which will positively prevent the admission of air into the radiator when the condensation of the steam has produced a partial vacuum.

A further object of my invention is to provide a device adapted to be attached to radiator air vent valves which will permit the passage therethrough of air from the radiator but will prevent the return of air to the radiator upon the condensation of the steam therein.

A still further object of my invention is to provide a device of the character described which will be simple in construction, inexpensive in manufacture, and efficient in use.

My invention, generally described, consists of a vacuum attachment adapted to be secured to an air vent valve and comprising a normally seated valve controlling a port leading from the air vent valve to the atmosphere, means for un-seating the valve when pressure of steam in the system with which the air vent valve communicates slightly exceeds the atmospheric pressure, and means for automatically seating the valve and retaining the same seated when the pressure in the system falls a predetermined degree.

My invention further consists in an improved air vent valve for radiators comprising a float chamber communicating with the radiator, a float within said chamber controlling a vent port, and an air chamber located above the float chamber and communicating therewith near the bottom thereof.

My invention will be more fully described hereinafter with reference to the accompanying drawings, in which the same is illustrated as embodied in a convenient and practical form and in which Figure 1 is a central sectional view; Fig. 2 a plan view, the cap on the cover having been removed; Fig. 3 a plan view of the under side of the vacuum attachment disconnected from the vent valve, and Fig. 4 an elevational view of a modified means of connecting the vacuum attachment to the vent valve.

The same reference characters are used to designate the same parts in the several figures of the drawings.

Reference character A indicates the casting of an automatic air vent valve in which is mounted concentrically a cylinder A' the interior of which communicates with the space around the same inclosed by the cas-

ing, by means of one or more ports *a* extending through the cylinder adjacent the lower end thereof. The casing extends above the top of the cylinder so as to form an air chamber communicating with the space between the cylinder and casing. A float *B* is located within the cylinder *A'* and carries at its upper end a valve *b* adapted to co-operate with a valve seat *b'* formed on the under surface of the upper end *a'* of the cylinder *A'*. A tube *B'* projects above the valve seat *b'* and communicates with the port therethrough. The lower end of the tube *B'* is supported in a seat in the end wall *a'* of the cylinder, while its upper end extends through the end wall *A'* of the casing *A* and is supported by a surrounding flange *a'*. The lower end of the casing is closed by a cap *A'* surrounding and in screw-threaded engagement therewith. A pin *a'* is provided upon the cap *A'* which serves as a stop for limiting the downward movement of the float *B*.

A' designates a coupling through which extends a passage-way from the interior of the cylinder *A'*. The coupling *A'* is secured around an opening in the cylinder *A'* and extends through the casing *A*. The end of the coupling which projects through the casing is exteriorly screw-threaded and is adapted to be attached to a radiator by means of an interposed coupling *a'* one end of which surrounds and is in screw-threaded engagement with the end of the coupling *A'* while its other end is adapted to engage a screw-threaded hole in a radiator coil.

The device above described constitutes an automatic air vent valve which operates as follows: During the first operation the air in the radiator passes freely through the valve. When steam enters the cylinder *A'* it condenses, gradually filling the float chamber formed therein below the coupling *A'* so that the float is lifted and the valve *b* closed against the co-operating seat thereby closing the vent port. The heat of the steam within the cylinder expands the air in the air chamber between the upper ends of the cylinder and casing and also the air within the space between the side walls of the cylinder and casing which constitutes an extension of the air chamber; a portion of the air is consequently expelled through the hole *a* and passes through the vent port. When the steam in the radiator is cut off the air in the air chamber contracts and draws the water from the float chamber through the port *a* allowing the float to fall and opening the vent port. When steam is again turned on to the radiator any air therein is expelled through the vent opening, such opening being immediately closed after the expulsion of the air by the steam expanding the air in the air chamber and forcing the water from the space between the cylinder and casing

into the float chamber and thereby elevating the float and closing the valve.

Vacuum attachment.—My improved vacuum attachment which is adapted to be used in connection with any form of automatic air vent valve such for instance, as that above described, comprises a base plate *C* supported upon the upper end of the valve casing *A* as by means of a flange *c* surrounding and in screw-threaded engagement with the upper end of the casing. The base-plate *C* is provided with an upwardly projecting flange *C'* around its periphery upon which is supported a diaphragm *D*. The diaphragm is preferably concave and formed of resilient metal. The diaphragm may be conveniently supported upon the base-plate by means of a peripheral flange surrounding the flange *C'*. Supported above the diaphragm is a stop plate *E* also preferably slightly concave and supported above the diaphragm by means of ears *e* depending from its periphery and engaging the flange around the diaphragm. The stop plate may be corrugated as indicated in Fig. 1 to increase its strength.

H indicates a cover removably supported upon the base *C* by means of a depending flange *H'*. The cover *H* has a hole *h* through which extends a stem *F* supporting at its lower end a ball valve *f*, the latter being located below the diaphragm and co-operating with a seat formed by a flange *d* around a central opening in the diaphragm. The stem *F* extends loosely through a hole in the stop plate *E* and projects within a chamber *h'* formed in the cover *H*. The chamber *h'* is closed by a removable cap *H'* which may be conveniently formed with an interiorly screw-threaded flange engaging an exterior screw-thread on the wall around the chamber.

The end of the stem *F* within the chamber *h'* is provided with an exteriorly screw-threaded enlarged portion *g* which is surrounded by a nut *G*. The lower end of the nut *G* rests upon the lower wall of the chamber *h'* around the hole *h* therethrough. The nut is provided with a squared portion, as shown in Fig. 2, which fits loosely within notches in the wall of the chamber *h'* so as to prevent rotation of the nut within the chamber, but so as to permit oscillation of the stem.

By supporting the nut *G* loosely within the chamber *h'* it is permitted to oscillate slightly and thereby insure the valve *f* closely seating against the flange *d*. If the valve *f* were not supported so as to be slightly oscillatory it would be impossible to secure a close fit between the same and its seat.

The operation of my improved vacuum valve is as follows: The diaphragm *D* normally engages the ball-valve *f* but upon its

130

under surface being exposed to pressure slightly greater than that of the atmosphere it is lifted so as to move the flange *d* away from the valve *f* thereby permitting the 5 venting of air from the cylinder *A'* through the diaphragm, and thence to the atmosphere through the space formed between the flange *H*² of the cover and the flange *C'* of the base plate *C*, such space being due to the 10 lugs *e* on the stop plate *E* which are interposed between the flanges on the diaphragm and on the cover, as indicated in Fig. 3.

When the pressure in the system falls to a predetermined degree, preferably to a 15 point slightly above atmospheric pressure, the diaphragm is deflected downwardly so as to again force the seat *d* thereon against the ball-valve *f*. The admission of air to the cylinder *A'* and thence to the radiator 20 when the pressure in the system is below the atmosphere is consequently prevented. The position of the valve *f* relatively to the diaphragm may be readily adjusted by rotating the enlarged portion *g* on the upper end of 25 the stem relatively to the surrounding nut *G*. In this manner the opening and closing of the port through the diaphragm may be accurately regulated.

The vacuum attachment may be connected 30 to the vent valve by an interposed elbow *K* as shown in Fig. 4. By the employment of an elbow the vacuum attachment occupies a position at one side of the vent valve so that the coupling *A*² may be engaged directly 35 with the hole in the radiator without the necessity of interposing an additional coupling *a*² as is necessary when the vacuum attachment is located directly above the vent valve as shown in Fig. 1. The elbow at one 40 end engages within the flange *c* on the base-plate *C* of the vacuum attachment while its other end aligns with the upper end of the casing of the vent valve and is secured thereto in any suitable manner, as by means of a 45 ring *L* having interior right and left screw-threads engaging exterior screw-threads on the upper end *A*³ of the casing and the lower end of the elbow.

From the foregoing description it will be 50 observed that I have invented an improved vacuum attachment for steam heating systems which may be readily attached to an automatic air vent valve and by means of which air may be expelled from the system 55 when the pressure therein is slightly above atmospheric pressure, but which will effectively prevent the admission of air to the system when the pressure therein has fallen to a pre-determined degree, thereby preventing 60 the partial vacuum formed in the system by the condensation of the steam being destroyed.

It will also be observed that I have invented an improved automatic air valve for 65 radiators which is extremely sensitive owing

to the enlarged air chamber the expansion and contraction of air within which controls the opening and closing of the vent port.

Having now fully described my invention, what I claim as new and desire to secure by Letters Patent is:

1. A valve for steam heating systems comprising a diaphragm having a port therethrough, means for supporting said diaphragm in position to expose one surface 75 thereof to pressure in the system, and the other side thereof to atmospheric pressure, a valve coöperating with said port to open and close the same, and means extending through said port for supporting said valve in position to be engaged and disengaged by the diaphragm.

2. A valve for steam heating systems comprising a diaphragm having a port therethrough, a base plate upon which said diaphragm is mounted and through which one surface of said diaphragm is exposed to pressure in the system, a cover supported upon said base-plate and inclosing the opposite side of the diaphragm, said opposite side of the diaphragm being exposed to the atmosphere, a valve coöperating with said port to open and close the same, and means supported by said cover and extending through the port in said diaphragm for supporting said valve in position to be engaged and disengaged by the diaphragm.

3. A valve for steam heating systems comprising a diaphragm one surface of which is concave and the other surface of which is convex, said diaphragm having a port therethrough, means for supporting said diaphragm in position to expose its convex surface to pressure in the system and its concave surface to pressure of the atmosphere, 100 a valve coöperating with said port to open and close the same, a stop plate supported above said diaphragm to limit its movement, and means extending through said stop plate and said port for supporting said valve in 110 position to be engaged and disengaged by the diaphragm.

4. A valve for steam heating systems comprising a concavo-convex diaphragm having a port therethrough, the concave surface of 115 said diaphragm being exposed to the atmosphere, a base-plate upon which said diaphragm is mounted and through which its convex surface is exposed to pressure in the system, a stop plate located in position to 120 limit the movement of said diaphragm, a cover supported upon said base plate and inclosing said stop plate, a valve coöperating with said port to open and close the same, and means supported by said cover and extending through said stop plate and said port for supporting said valve in position to be 125 engaged and disengaged by the diaphragm.

5. A valve for steam heating systems comprising a diaphragm having a port there-

through, means for supporting said diaphragm in position to expose one surface thereof to pressure in the system and the other surface thereof to atmospheric pressure, a valve coöperating with said port to open and close the same, and an oscillatory rod extending through said port for supporting said valve in position to be engaged and disengaged by the diaphragm.

10 6. A valve for steam heating systems comprising a diaphragm having a port therethrough, a base-plate upon which said diaphragm is mounted and through which one surface thereof is exposed to pressure in the system, the other surface of said diaphragm being exposed to the atmosphere, a cover supported upon said base-plate and inclosing the atmospheric side of the diaphragm, a valve coöperating with said port to open and close the same, an oscillatory rod extending through said port for supporting the valve in position to be engaged and disengaged by the diaphragm, and means for supporting said rod upon said cover.

25 7. A valve for steam heating systems comprising a resilient diaphragm having a port therethrough, a base-plate upon which said diaphragm is mounted and through which one surface thereof is exposed to pressure in the system, the other surface of said dia-

phragm being exposed to the atmosphere, a valve coöperating with said port to open and close the same, an oscillatory rod extending through said port for supporting said valve in position to be engaged and disengaged by the diaphragm, a support for said valve mounted upon said base plate on the opposite side of said diaphragm from said valve, and means for connecting said rod to said support.

8. In an automatic vent valve having an inlet and an outlet, the combination with a float for controlling the outlet, of a cylinder forming a float chamber within which said float is located, a casing surrounding and spaced apart from said cylinder to form an air chamber between the upper ends of said cylinder and casing, said air chamber communicating with said float chamber near the bottom thereof through the space between said cylinder and casing, and a tube extending through said air chamber with which said outlet communicates.

In testimony whereof, I sign this specification in the presence of two witnesses.

GEORGE D. HOFFMAN.
